UNITED STATES PATENT OFFICE.

CHARLES F. LEFEVER, OF PLYMOUTH, MICHIGAN, ASSIGNOR TO DAISY MANUFACTURING CO., OF PLYMOUTH, MICHIGAN, A CORPORATION OF MICHIGAN.

POPGUN.

Application filed May 10, 1922. Serial No. 559,737.

To all whom it may concern:

Be it known that I, CHARLES F. LEFEVER, a citizen of the United States of America, residing at Plymouth, in the county of Wayne and State of Michigan, have invented certain new and useful Improvements in Popguns, of which the following is a specification, reference being had therein to the accompanying drawings.

10 The invention relates to pop guns of that type in which a cork is ejected from the muzzle of the barrel by the air compressed by a spring pressed plunger released by a trigger. It is the object of the invention to obtain a simplified construction for compressing the spring and one which may be actuated by a break-down movement. To this end the invention consists in the construction as hereinafter set forth.

20 In the drawings:

Figure 1 is a longitudinal section through the gun;

Figure 2 is a similar view showing a broken down position which effects the compression of the spring;

Figure 3 is a rear end view of the gun in broken down position;

Figure 4 is a bottom plan view partly broken away.

30 A is the barrel of the gun in which is arranged the spring B with its end engaging an abutment C, preferably a tongue struck inward from the barrel. D is the plunger at the forward end of the spring and E is an abutment for said plunger, preferably formed by a turned in flange at the muzzle of the barrel. F are frame members projecting downwardly from the breech end of the barrel between which is placed the trigger member G pivoted to the cross pin H and having the sear I for engaging the hooked end J of a shank K for the plunger D. L is the stock which has a break-down connection to the barrel formed by the projecting bifurcated members M pivotally attached at N to the frame members F.

40 To effect the compression of the spring by the breaking-down movement of the barrel and stock, I have provided a member connected with the stock and projecting into the barrel in a position to engage with the hook J. This member O preferably also forms the trigger guard O', being secured between the furcations of the member M as well as between the frame members F. The

construction is such that when the gun is in normal position, the end of the member O will be sufficiently forward in the barrel to clear the hook J when the plunger D is against the abutment E. On the other hand, when the stock and barrel are broken down, the member O will swing rearward engaging the hook J and carrying the same, together with the shank K, rearward until said hook engages the sear I. The stock and barrel may then be returned to normal position, which will leave the hook J in engagement with the sear until released by the pulling of the trigger G. The proportion of parts is such that when the gun is in broken-down position, the end of the trigger G will remain between the furcations of the member M, so that it is impossible to pull the trigger or disengage the sear until the gun is restored to normal position. Thus the construction is one which dispenses with any pivoted break-down connection between the stock and plunger, or with the use of any lever independent of the stock and frame for compressing the spring.

50 What I claim as my invention is:

1. In a toy gun, the combination with a barrel and a spring pressed plunger therein, of a stock having a break-down connection with said barrel, a hooked shank for said plunger, a combined trigger and sear for engaging said hooked shank and for releasing the same, and a member projecting from said stock through the side of and into the barrel adapted to engage said hooked shank during the breaking-down movement to force the same into engagement with said sear.

60 2. In a toy gun, the combination with a barrel and a spring pressed plunger therein, of a stock having a break-down connection with said barrel, a hooked shank for said plunger, a combined sear and trigger for engaging and releasing said hooked shank, and a member secured to said stock normally forming the trigger guard, said member projecting into said barrel and forming a means for engaging said hooked shank during the breaking-down movement to move the same into engagement with said sear.

70 3. In a toy gun, the combination with a barrel having laterally projecting spaced portions at the breech end thereof, of a stock having a break-down connection with

- 5 said barrel formed by bifurcated projections pivotally attached to said spaced laterally projecting portions, a trigger and sear pivoted in said barrel and projecting
 10 between said bifurcated members, a spring pressed plunger in the barrel, a hooked shank for said spring pressed plunger adapted to engage with said sear, and a member projecting from said stock to form
 15 a trigger guard having an extension into said member engaging said hooked shank in the breaking-down movement of the gun to actuate said shank into said engagement with the sear.
 20 4. In a toy gun, the combination with a barrel, of a spring-pressed plunger therein, a stock having a break-down connection with said barrel, a hooked shank for said plunger, a trigger and sear for engaging and releasing said hooked shank, and a member projecting from said stock for actuating said hooked shank upon the breaking-down movement of the barrel to engage the same with said sear, said break-down
 25 connection forming a guard for said trigger to prevent actuation of the same while the gun is broken down.
 5. In a toy gun, the combination with a barrel, of a spring-pressed plunger therein, a hooked shank for said plunger, a trigger and sear pivoted in said barrel adapted to engage and release said hooked shank, a stock, a break-down connection between said

35 stock and barrel including spaced members on the barrel and stock between which said trigger projects, said spaced members being pivoted to each other, and a trigger guard extending between said spaced members and projecting into the barrel to form a means for compressing the spring and engaging said hooked member with the sear upon the breaking-down of the gun.

40 6. In a toy gun, the combination with a barrel and a spring-pressed plunger therein, of a stock having a break-down connection with said barrel, a shank for said plunger, a combined sear and trigger for engaging and releasing said shank, and a member rigidly secured to said stock and projecting into said barrel, said member being adapted to engage said shank during the breaking-down movement to force the same into engagement with said sear.

45 7. In a toy gun, the combination with a barrel and a spring-pressed plunger therein, of a stock pivotally connected to said barrel, a shank for said plunger, a combined trigger and sear for engaging said shank and for releasing the same, and a member rigidly secured to said stock and projecting through the side of and into said barrel, said member being adapted to engage said shank during the breaking down movement to force the same into engagement with said sear.

50 55 In testimony whereof I affix my signature,
 60 CHARLES F. LEFEVER.
